UNITED STATES PATENT OFFICE.

JOHN G. DEITZ, OF MACON, GEORGIA.

COVER FOR GLASS TUMBLERS, VESSELS, AND THE LIKE.

1,178,633.

Specification of Letters Patent. Patented Apr. 11, 1916.

Application filed October 9, 1915. Serial No. 55,034.

To all whom it may concern:

Be it known that I, JOHN G. DEITZ, a citizen of the United States, residing at Macon, in the county of Bibb and State of Georgia, 5 have invented new and useful Improvements in Covers for Glass Tumblers, Vessels, and the like, of which the following is a specification.

The invention relates to a cover, and more 10 particularly to the class of cover attachments for receptacles.

The primary object of the invention is the provision of a cover of this character which can be quickly attached to and detached from drinking tumblers, bowls, cups, 15 pans and all other vessels of a like nature, irrespective of the sizes and shapes thereof so that the contents can be protected from dust and dirt and the atmospheric air excluded therefrom.

Another object of the invention is the provision of a cover of this character wherein the same will snugly fit the mouth edge or other portion of the body of a receptacle 25 or vessel and will completely seal the mouth thereof, the cover being fitted to the receptacle or vessel without the necessity of the use of adhesive or other fastening medium and will serve as a seal to exclude air and 30 dust from the contents thereof and also as a protector for such contents to prevent the spilling of the same should the receptacle or vessel be disturbed when at rest or carried from one point to another.

35 A further object of the invention is the provision of a cover of this character which is extremely simple in construction, thoroughly reliable and efficient in its purpose, strong, durable, and inexpensive to manufacture.

40 With these and other objects in view, the invention consists in the construction, combination and arrangement of parts as will be hereinafter fully described, illustrated in 45 the accompanying drawing, and pointed out in the claim hereunto appended.

In the drawing, Figure 1 is a side elevation of a drinking tumbler showing the cover constructed in accordance with the invention, applied and in sealing position. Fig. 2 is a vertical longitudinal sectional

view thereof. Fig. 3 is a fragmentary side elevation prior to the closing of the cover. Fig. 4 is a perspective view of the cover removed from the tumbler. Fig. 5 is a plan 55 view of the cover when in flat condition.

Similar reference characters indicate corresponding parts throughout the several views in the drawing.

Referring now to the drawing in detail, 60 A designates generally a drinking tumbler which is of the ordinary well known construction having the flared body to present a widened mouth B, as usual, although the shape of the tumbler forms no part of the 65 present invention and this style is merely shown to illustrate the application of the cover and the use thereof associated with the same, as will be hereinafter fully described.

70 The cover comprises an inverted truncated substantially conical-shaped body 5 preferably made from flexible material, such as paper or cloth, although it may be made from any other pliable light material. The 75 edges 6 and 7 at the smaller and larger ends respectively of the body 5 being slightly arched so that the said body will conveniently fit the body of the tumbler A which is slipped into the said body 5 through the 80 larger end thereof whereby the smaller end will snugly embrace the said body A of the tumbler when the body 5 is moved upwardly over the flared portion B of the tumbler and thereafter the free wider end of the body 5 85 is twisted for the sealing of the tumbler to protect the contents thereof, as will be clearly apparent in Fig. 1 of the drawing.

In the formation of the body 5, the overlapped or meeting ends 8 are secured together through the medium of suitable adhesive or other means for the fastening of the said overlapped ends to each other to present a unitary body structure. Of course, it is to be understood that the conformation 90 of the body 5 can be varied accordingly with respect to the shape of the tumbler, receptacle or vessel so that the same will make a readily attachable and detachable cover therefor.

100 From the foregoing, it is thought that the construction and manner of employing the

cover will be clearly understood, and therefore, a more extended description has been omitted.

What is claimed, is:—

- 5 The combination with a receptacle having a flared mouth end, of a sleeve-like flexible body smaller at one end than at the other for permitting the detachable engagement of the body upon the receptacle by the slipping of
10 said body on to the receptacle to bring the

smaller end of the body into engagement with the flared mouth end of the receptacle whereby the body can be closed over the mouth of said receptacle.

In testimony whereof I affix my signature in presence of two witnesses.

JOHN G. DEITZ.
